METHOD OF AND APPARATUS FOR CASTING
DEOXIDIZED COPPERWilliam K. Thompson, Woodbridge, N. J., assign-
or to The American Metal Company, Limited,
New York, N. Y., a corporation of New York

Application October 19, 1935, Serial No. 45,692

7 Claims. (Cl. 22—73)

My present invention relates to a method of and apparatus for producing and casting high density degassed metals, and more particularly to producing high density deoxidized copper.

According to my present invention the copper or other metal to be cast is melted in the ordinary way in a conventional type furnace and degassing or deoxidation of the molten metal is effected in a suitable apparatus by the use of either gaseous or solid deoxidizing or reducing agents or a combination of such gaseous and solid agents capable of deoxidizing metallic or non-metallic oxides. The deoxidized metal is conducted from its deoxidizing chamber through a vacuum chamber and there cast in vacuo. The method of and apparatus for carrying out my invention will be better understood from the detailed description which follows when considered in conjunction with the accompanying drawings, wherein—

Figure 1 is a vertical section through a vacuum casting apparatus embodying my invention.

Fig. 2 is a similar section, partly in elevation, showing a modification of my invention suitable for continuous casting.

Fig. 3 is a fractional top plan view of the apparatus shown in Fig. 2.

Fig. 4 is a top plan view of a removable portion of the casting ring cover of the apparatus shown in Figs. 2 and 3.

Referring first to Fig. 1 of the drawings the apparatus which may be termed a casting well consists of a substantially U-shaped member 10 comprising upright branches 12 and 13 which are connected at their bottoms by a deep, substantially V-shaped trough-forming portion 14. The top of the branch 13 is formed with a lateral extension 15 which in turn has a reversely or downwardly directed branch or arm 16. The casting well may be constructed in any suitable manner from any number of parts, and preferably as herein shown consists of an enclosing wall or steel shell 17 provided with a suitable refractory lining 18 providing numerous connecting chambers. The branch 12 at its top is closed by a refractory plug 19 having a funnel opening 20 therein through which the molten metal may be poured into the receiving chamber of the well from a tilting furnace or the like 21, and a second opening 22 through which extends a gas supply pipe 23 adapted to be held in place in said plug by a bushing packing 24. The lateral extension 15 of the apparatus has its bottom wall longitudinally grooved as shown at 25 and formed with a basin 26 having an overflow lip 27. The downwardly extending branch 16 which may

be said to constitute a discharge spout is formed at its lower end with a thickened wall 28 having a reduced tubular extension 29 over which latter is axially movable a collar 30 having an annular tongue 31 on its lower face. Movement of the collar 30 over the reduced extension 29 may be controlled by a plurality of fluid-operated pistons 32 movable within cylinders (not shown) formed and circumferentially disposed within the thickened wall 28. The top wall of the lateral extension 15 is formed with openings therethrough, 33 and 34, in alignment with the openings or chambers in the branches 13 and 16 respectively, and the steel shell 17 directly above the openings 33 and 34 has sight openings 35 and 36 respectively which are provided with suitable transparent material hermetically sealed within said shell. Extending through the wall of the branch 16 and communicating with the interior chamber thereof is a duct 37 leading to the atmosphere, which duct is provided with a manually controlled vent valve 38.

Above the lateral extension 15 the apparatus is formed with a chamber 39 having a gas inlet 40 and a duct 41 provided with a manually controlled valve 42, the duct 41 leading to a powerful vacuum pump (not shown).

The molten metal, while passing through the apparatus, may be maintained in the molten state by suitable heating means; for example, the refractory linings in the branches 12, 13 and 16 may have incorporated therein suitable electric heating elements 43, 44 and 45, respectively, while the lateral extension 15 between the basin 26 and the refractory arch thereover may be provided with an electric heating unit 46 which by radiant heat will maintain the metal in the basin 26 in the molten state. The metal in the trough 14 may be maintained in the molten state by electric induction heating and said trough is formed as an electric induction furnace of the type disclosed in the Wyatt Patent No. 1,201,671, and comprises a laminated iron core having end legs 47 and a central leg 48, around which latter is disposed a circular primary winding 49. The central leg 48 and the winding thereon are mounted in a refractory housing 14a which may be integral with the refractory lining of the trough-forming portion 14, and spaced therefrom at its opposite sides to provide a V-shaped channel. This V-shaped channel when filled with molten metal constitutes the secondary of the induction furnace and by a mode of circulation in which hot metal leaves and cooler metal enters the channel, the metal in the bottom of the cast-

ing well above the induction furnace will be maintained in the molten state. The specific character and location of the various heating elements, however, do not constitute the essence of the present invention.

The metal treated in the apparatus may be cast in suitable molds 50, which, as herein shown, are of the water-cooled type and consist of a water-cooled casing 51 mounted on a stool 52, 10 supported in turn upon a water-cooled base plate 53. A tongue and groove or other suitable airtight connection may be provided between the mold casing and the stool, and in order to insure an hermetic seal between the mold and the apparatus, the top of the casing 51 is formed with an annular groove 54 which is complementary to the annular tongue 31 on the collar 30, and a packing washer 55 of suitable material may be interposed between said tongue and groove joint. 15 20 Of course, a suitable packing will also be used at the joint between the casing 51 and the stool 52.

The method of casting degassed metals in accordance with the apparatus above described is substantially as follows: Starting with an empty cold furnace, a mold 50 is first placed in position, as shown, to provide an airtight seal with the branch or discharge nozzle 16. This is accomplished by properly aligning the mold, the stool and the tubular extension of the branch 16, and moving the collar 30 into sealing relation with the top of the mold casing by the fluid-operated pistons 32. The funnel-shaped opening 20 in the plug 16 is then temporarily closed by a suitable stopper (not shown) and the air is entirely displaced from the apparatus and the mold cavity by the admission of non-oxidizing or reducing gas into the various chambers through the pipe 23. While this gas is being admitted the valve 42 is closed; hence, the only exit for the gas is through the duct 37, the valve 38 of which is left open. After a period of time the effluent gas through the pipe 37, if combustible, may be ignited, and in the meantime the flow of gas into the apparatus is increased by admitting gas 40 through the gas inlet 40. After the air is entirely displaced by the atmosphere of non-oxidizing or reducing gas or the partial pressure of the oxygen remaining has been reduced to such a low value that its presence is harmless to the metal, heating of the furnace is started while continuing the flow of gas therethrough, after which the stopper is removed from the funnel opening 20 and the gas issuing at that point is then ignited, if combustible. When the furnace reaches proper temperature, molten metal, for example copper, is then poured in a relatively fine stream from the tilting furnace 21 into the funnel 20 through the flame and through the upwardly moving current of gas, and the metal after filling 50 the trough 14, will gradually rise into the branches 12 and 13. The rise of the metal in the branch 13 is watched through the sight opening 35 and when said metal has reached a suitable level the pouring is suspended and the valve 38 and the valve (not shown) controlling the gas inlet 40 are closed. The valve 42 is then opened, thereby subjecting the chamber 39 and the chambers or passages in the branches 13, 15 and 16, as well as the mold cavity, to the action of 60 the vacuum pump (not shown), and establishing a gas pressure differential above the metal in the branches 12 and 13, causing the metal in branch 13 to rise and overflow into the basin 26. The metal flowing into basin 26 is spread out into a 70 sheet of small depth. This and the retardation of 75

the flow in the basin 26 allows the vacuum to draw out practically all of the gases dissolved in the metal. To accomplish this the area of the basin 26 is of sufficient magnitude for the vacuum to degas the molten metal in the limited time of its flow through the basin. Simultaneously, or just prior to the overflowing of the metal from the basin taking place, the pouring of the metal into the branch 12 is resumed, whereupon the metal will continue to flow into the basin 26 and overflow therefrom over the lip 27 down into the mold cavity. The progress of filling the mold is watched through the sight opening 36, and when the mold is full, the casting is allowed to cool, after which the valve 42 is closed and gas is again admitted through the gas inlet 40. Upon the admission of gas into the chamber 39 the metal in the branch 13 will fall, due to the lowering of the gas pressure differential in branches 12 and 13, the valve 38 is again opened, the gas issuing from the duct 37 is ignited and the pouring of metal suspended. The seal on the mold is then broken by raising the collar 30 and the mold with the casting therein is removed and replaced by an empty mold which has preferably been washed out with a non-oxidizing gas. The continual flow of gas during this change of molds protects the molten metal in the apparatus from re-oxidation. When the empty mold has been clamped in place, gas inlet 40 is closed, valve 42 is opened and the casting operation is proceeded with as described above.

In the operation of the apparatus as described, the vacuum in the well and mold cavity has to be built up between each casting operation. Accordingly, a vacuum pump of large capacity relative to the volume to be evacuated, is required. Applicant has found that with a ratio of pump capacity to volume to be exhausted of 1:1, it would take about five minutes to reach a vacuum of 29.8 inches of mercury, or one which would permit the gas under atmospheric pressure in the branch 12 to support a column of copper at 2100° F. in the branch 13 of approximately 47 inches.

In the operation above described, the molten metal in passing through the reducing or non-oxidizing gas in the branch 12 from the level C to the level B (Fig. 1) will become deoxidized. The distance of immersion of the pipe 23 in the gas filled chamber or branch 12 can be varied at will, as it will be obvious that said pipe can be adjustably held within the packing bushing 24. However, the pipe 23 should have as great a depth of immersion as possible without dipping into the molten metal.

In Figs. 2 to 4 I have shown an apparatus with which substantially continuous casting is possible. In this embodiment of my invention I employ a casting wheel which consists of a circular frame or platform 60 which is rotatable about its axis, 60 said platform having upstanding parallel walls 61, which above their bottoms are bifurcated or double-walled, as shown at 62, to provide annular troughs 63. Mounted on the base of the rotatable frame in definitely circumferentially 65 spaced relation are stools 65 upon each of which is mounted a water-cooled casing 66 to provide a plurality of casting molds. The top of each of the casings 66 is formed with a removable extension or top 67, the function for which will 70 presently appear. Extending over the rotatable frame 60 and supported in airtight definitely fixed relation to the casting well is a casting ring cover 70 having a top 71 and depending parallel flanges 72 adapted to telescope with the up- 75

standing walls 62 of the platform and spaced depending flanges or rings 73 adapted to extend down into the troughs 63. To provide for free relative rotation between the fixed cover 10 and the movable platform 60, roller bearings 14 are mounted between the tops of the walls 61 and the under side of cover top 11. To insure an hermetic seal between the rotatable platform and stationary cover ring a mercury seal may be provided between the depending flanges 73 and the troughs 63. If desired, the mercury may be covered by several inches of high-flash-point oil to maintain the airtight condition between the elements of the casting ring and prevent evaporation of the mercury. A removable portion 75 of the cover may be provided as a means of gaining access to the interior of the casting ring to remove the cast metal from the molds after solidification. Preferably, this removable cover will be located rearwardly adjacent the casting station, thereby permitting cooling of the castings during the complete circuit of the casting ring in order to reach the casting removing station. Of course, during the continuous operation, the cover portion 75 will provide an hermetic seal for both the casting platform and the ring cover proper.

In the operation of this continuous casting process the manipulation is substantially the same as that described with reference to the construction shown in Fig. 1 for intermittent casting, except that a complete round of billets or other forms is cast before breaking the vacuum completely between the vacuum chamber 39 and the chamber provided by the casting wheel platform and its cover. However, between casting individual billets or shapes the flow over the basin 26 is intermittently cut off by bleeding-in through the gas inlet 40 a small quantity of gas which lowers the vacuum slightly, thus causing the metal to cease flowing into the basin. However, not a sufficient loss of vacuum is permitted to greatly alter the level differential between the planes A and B. When a complete round of billets is cast the removable portion 75 of the ring cover is removed, and the removable extensions 67 are successively taken off of the molds, thus leaving the ends of the castings accessible to a set of tongs or other means by which the castings may be removed from the molds. After all of the castings have been removed the cover portion 75 is replaced to again seal the mold-containing chamber, the gas flow is increased by admitting additional gas through pipe 40 to sweep the air out of the molds and the mold-containing chamber. When the partial pressure of original air in the molds and chamber is reduced to a harmless amount, said chamber is evacuated and the procedure of casting another round is repeated.

While the apparatus hereinbefore described is primarily designed for use with gas to effect deoxidation, it will be appreciated that solid carbonaceous material, or a combination of both solid and gaseous deoxidizers, may be employed with but slight modification of the apparatus; also, that where deoxidized metal is to be poured into the apparatus for casting, an inert non-oxidizing gas such as nitrogen may be used instead of an inflammable reducing gas. It will also be understood that while I have shown and described certain preferred embodiments of my invention, I do not wish to be limited to the details of procedure and construction disclosed, since it will be apparent to those skilled in the art that

changes may be made in said procedure and construction within the range of engineering skill without departing from the spirit of the invention.

What I claim is:

1. The method of casting metal, which comprises displacing the atmospheric air by a reducing or non-oxidizing atmosphere in a chamber having two upright branches connected at their bottoms, simultaneously charging molten metal 10 and a reducing gas down into one branch of the chamber until the molten metal extends up into said branches below the tops thereof and flowing the molten metal during the charging thereof into the chamber through a current of the reducing gas moving in a counter direction to the stream of molten metal, while maintaining the reducing atmosphere above the surface of the molten metal in the other branch, withdrawing the reducing atmosphere from the part of the chamber in open communication with the second mentioned branch and creating in its stead in said portion of the chamber a high vacuum, and then causing the molten metal from the chamber to flow through said high vacuum into a mold 23 exposed to said vacuum.

2. The method of casting metal, which comprises displacing the atmospheric air by a reducing or non-oxidizing atmosphere in a chamber having two upright branches connected at their bottoms, simultaneously charging molten metal and a reducing gas down into one branch of the chamber until the molten metal extends up into said branches below the tops thereof and flowing the molten metal during the charging thereof into the chamber through a current of the reducing gas moving in a counter direction to the stream of molten metal, while maintaining the reducing atmosphere above the surface of the molten metal in the other branch, withdrawing the reducing atmosphere from the part of the chamber in open communication with the second mentioned branch and creating in its stead in said portion of the chamber a high vacuum, then continuing the counter flow of reducing gas and molten metal into the first branch of the chamber whereby to cause the molten metal in the second branch to overflow said branch and flow through said high vacuum into a mold exposed to said vacuum.

3. The method according to claim 2, supplemented by the step of charging a reducing atmosphere into the vacuum chamber after the metal casting in the mold has solidified.

4. The method of casting metal, which comprises charging molten metal down into one branch of a chamber having two upright branches connected at their bottoms containing a reducing or non-oxidizing atmosphere until the molten metal extends up into said branches below the open tops thereof, then withdrawing the said atmosphere from that portion of the chamber in open communication with the other of said branches and creating in its stead in said portion of the chamber a high vacuum, then continuing to charge molten metal into the first branch of the chamber thus causing said metal in the vacuum chamber branch to discharge over a basin into a mold exposed to said vacuum until said mold is filled, then checking the flow of metal over the basin by temporarily ceasing the metal pouring and bleeding into the evacuated chamber a small amount of reducing or oxidizing gas to lower the vacuum therein while removing the filled mold and presenting an empty mold to be 75

filled from below the basin, and then again creating a high vacuum in said portion of the chamber containing the basin and the mold, and again charging molten metal into the first branch of the chamber, thereby causing the metal in the other branch to rise and discharge over the basin into the mold.

5. Apparatus for vacuum casting metals, comprising a chamber for receiving molten metal, a 10 rotatable casting frame carrying a plurality of molds, a ring cover for the casting frame providing an enclosing chamber for, and open to, all the molds, a vacuum chamber in open communication with both the molten metal chamber and the enclosing chamber for the molds, and means for providing an hermetic seal between the rotatable casting frame and its ring cover while permitting relative movement therebetween, said ring cover having a removable portion to permit access to the molds, and the molds each having a removable extension or top, which, when removed, facilitates removal of the casting from the mold through the top thereof and through the opening provided by the removable portion of the cover.
- 15 6. Apparatus for casting non-oxidized, de-gassed metal, comprising a molten metal receiving chamber having at least two upright branches connected together at their bottoms, one of said branches at its top being open to an overflow chamber having a discharge spout leading to a casting mold chamber which is in hermetically sealed relation to the overflow chamber, a plurality of molds in said last mentioned chamber with each mold adapted to be brought into alignment with the discharge spout, means for charging the mold chamber and the overflow chamber with a non-oxidizing gas, and means for providing a vacuum in the overflow chamber and in the mold chamber for creating a gas pressure differential in the branches of the receiving chamber whereby to cause the molten metal to overflow from one branch into the overflow chamber above it, and from there down the discharge spout into the molds in the casting mold chamber.
- 20 25 30

10 15 20 25 30

rality of molds in said last mentioned chamber with each mold adapted to be brought into alignment with the discharge spout, and means for providing a vacuum in the overflow chamber for creating a gas pressure differential in the branches of the receiving chamber whereby to cause the molten metal to overflow from one branch into the overflow chamber above it, and from there down the discharge spout into the molds in the casting mold chamber.

7. Apparatus for casting non-oxidized, de-gassed metal, comprising a molten metal receiving chamber having at least two upright branches connected together at their bottoms, one of said branches at its top being open to an overflow chamber having a discharge spout leading to a casting mold chamber which is in hermetically sealed relation to the overflow chamber, a plurality of molds in said last mentioned chamber with each mold adapted to be brought into alignment with the discharge spout, means for charging the mold chamber and the overflow chamber with a non-oxidizing gas, and means for providing a vacuum in the overflow chamber and in the mold chamber for creating a gas pressure differential in the branches of the receiving chamber whereby to cause the molten metal to overflow from one branch into the overflow chamber above it, and from there down the discharge spout into the molds in the casting mold chamber.

WILLIAM K. THOMPSON.
